LOUIS MACKENZIE AND WILLIAM RICHARDSON, JR., OF ENSLEY, ALABAMA.

COAL-WASHER JIG.

Application filed March 18, 1922. Serial No. 544,863.

To all whom it may concern:

Be it known that we, LOUIS MACKENZIE and WILLIAM RICHARDSON, Jr., citizens of the United States, and residents of Ensley, Alabama, have invented certain new and useful Improvements in Coal-Washer Jigs, of which the following is a specification.

This invention relates to jigs for separating coal or other minerals having different specific gravities and particularly to means for reciprocating the plungers of such jigs and to means for guiding said plungers.

One object of the invention is to provide a plunger having corner guide shoes which are adjustably secured to the plunger so that the same can be adjusted to compensate for wear.

Another object is to provide means secured to the plunger and arranged to reciprocate the latter and also to assist in guiding the plunger.

A further object is to provide resilient rubbing strips which are adjustably secured to the plunger so that they can be moved outwardly from time to time as they wear away.

Other objects will be apparent from the following description when read in connection with the accompanying drawings in

30 which

Fig. 1 is a vertical section through the cell of a coal washer jig showing our improved plunger and the means for reciprocating the same;

35 Fig. 2 is a sectional view on the line 2—2 of Fig. 1 showing an improved driving member;

Fig. 3 is a detail of a wear plate secured to the forked end of a connecting strap;

40 Fig. 4 is a diagrammatic view on a smaller scale showing a plunger mounted in a conventional form of a coal washer jig;

Fig. 5 is a horizontal section on the line 5—5 of Fig. 1;

45 Fig. 6 is a perspective view of one of the corner guide shoes secured to the plunger;

Fig. 7 is a perspective view of one of the ways secured to the corner of the plunger cell;

Fig. 8 is a perspective view showing one of the rubbing strips and the plate by which it is adjustably secured to the plunger.

Referring first to Fig. 4 the jig 10 is of any usual or suitable construction and is provided with a cell 12 within which the plunger 14 is mounted for vertical reciprocatory movement, the plunger being actuated by a driving member 16 which is keyed or otherwise secured to a driving shaft 18, carried in suitable bearings 20 secured to a rim 22 of the plunger cell.

A pair of upright connecting straps 24 are secured by bolts 26 to the bottom plate 28 of the plunger 14. These straps are forked at their upper ends 30 so that they straddle the driving shaft 18, and are provided with wear plates 32, Fig. 3, which are secured by suitable bolts 34, said bolts passing through ears 36 formed on the wear plates. Each connecting strap carries a roller 38 which is arranged to ride in a cam groove 40 formed in the driving member 16. These grooves are eccentric to the axis of the drive shaft 18, therefore as the latter is rotated it is clear that the connecting straps will be reciprocated and that their upper ends will be guided on the shaft 18 by the wear plates 32 secured to the forked portions of said straps.

The rollers 38 are carried by studs 42 which are provided with threaded portions 44 and clamped in place by suitable lock nuts 46. To the outer end of each stud is secured a grease cup 48 by which suitable lubricant can be introduced to the bearing surface through the conduit 50. Similar grease or oil cups 52 are carried by brackets 54 to lubricate the portion of the shaft 18 on which the wear plates 32 bear. The brackets 54 are provided with ears 56 through which the bolts 34, above referred to, pass. Below the rollers 38 the straps are secured to one another by a block 58 which is fastened by means of through-bolts 60. This holds the straps 24 in spaced relation so that the rollers 38 project the proper distance into the grooves 40 of the driving member 16, suitable spacing washers 62 being interposed between the inner surface of each

strap 24 and the adjacent surface of the driving member 16.

The plunger cell 12 is substantially square in plan and is provided near its lower end 5 with a lining 64 of such length that the plunger co-operates therewith throughout its stroke. At each corner the plunger cell is provided with a brace 66 the angular flanges 68 fitting flush against the inner 10 surface of the cell and being rigidly secured thereto by means of bolts 70; ears 72 being provided at the lower ends of the braces as shown clearly in Fig. 7. The inner surface of the braces are of arcuate formation 15 forming curved guideways 74. The plunger 14 is provided at its corners with guide shoes 76 shaped to nicely fit the ways 74. These shoes have horizontal portions 78 which are slotted at 80 for the reception 20 of bolts 82 by which they are adjustably secured to the plunger bottom. The guide shoes are also formed with downwardly depending ears 83 which are adapted to extend over the ends of resilient rubbing strips 84 25 to hold the ends in place and to thus prevent leakage past the plunger as it moves down. The rubbing strips 84 are made of suitable resilient material such as rubber belting or composition of canvas or other 30 fabric impregnated with rubber. These strips are secured by bolts 86 to plates 88 which are slotted at 90 for the reception 35 of bolts 92. This bolt and slot connection between the plates 88 and the plunger bottom permits of an adjustment whereby the rubbing strips can be moved outwardly to compensate for wear. This arrangement permits of a saving in the cost of maintenance of jigs of this type as the rubbing 40 strips can be adjusted outwardly to such extent that they are practically all used up before it is necessary to discard them. The outer portions 94 of the plates 88 are bent downwardly as shown in Fig. 1 and their undersurfaces are practically in alignment 45 with the lower edges of the ears 83 formed on the guide shoes.

From the above description it will be seen that the plunger is guided by the shoes 76 50 which ride on the ways 74, and by the forked end 30 of the connecting straps which ride on the shaft 18. It will be further understood that as the driving member 16 is rotated, a straight up and down movement will be transmitted to the plunger. The structure is such that wear on the parts 55 can be readily compensated for thus prolonging the life of the apparatus and cutting down the cost of the upkeep.

60 Though we have described with great particularity the details of the embodiment of our invention shown, it is not to be construed that we are limited thereto as

changes in arrangement and substitution of equivalents may be made by those skilled in 65 the art without departing from the invention as defined in the appended claims.

What we claim is:

1. In an apparatus of the class described, a substantially rectangular plunger having 70 curved corner guide shoes secured thereto, fixed ways secured to the cell in which said plunger operates arranged to co-act with said corner guide shoes, a drive shaft carrying a grooved driving member, a strap carrying means for engaging the groove in said driving member, said strap being forked at its upper end to engage said shaft and with said guide shoes serving to guide said plunger so that a straight line motion is imparted thereto by said driving member. 75

2. In an apparatus of the class described, a substantially rectangular plunger having curved corner guide shoes adjustably secured thereto, fixed ways secured to the cell 85 in which said plunger operates arranged to coact with said guide shoes, a shaft carrying a driving member for reciprocating said plunger, said member having a cam groove formed therein and a strap guided at one 90 end by said shaft and secured at the opposite end to said plunger and having secured thereto a member adapted to ride in said cam groove.

3. In an apparatus of the class described, 95 a substantially rectangular plunger having curved corner guide shoes adjustably secured thereto, fixed ways secured to the cell in which said plunger operates arranged to co-act with said guide shoes, a shaft carrying 100 a driving member for reciprocating said plunger, said member having identical eccentric grooves formed in the opposite sides thereof, a pair of straps forked on their upper ends and engaging said shaft on opposite sides of said driving member, means carried by said straps engaging said eccentric grooves for transmitting motion to said plunger. 105

4. In an apparatus of the class described, 110 a cell, a plunger guided therein, a drive shaft and means for imparting a straight line motion to said plunger comprising a strap secured at one end to said plunger and forked at the other end to slidably engage 115 said shaft and a driving member secured to said shaft having an eccentric groove formed therein and means carried by said strap and running in said groove.

5. In an apparatus of the class described, 120 a plunger having curved corner guide shoes, means for adjustably securing said guide shoes to said plunger, resilient rubbing strips and means for adjustably securing said rubbing strips to said plunger. 125

6. In an apparatus of the class described,

a plunger having curved corner guide shoes, means for adjustably securing said guide shoes to said plunger, resilient rubbing strips, slotted plates to which said rubbing strips are secured and bolts for adjustably securing said slotted plates to the plunger.

7. In an apparatus of the class described, a plunger having curved corner guide shoes having downwardly extending ears formed thereon, resilient rubbing strips whose ends

extend under and are held down by said ears, plates having downwardly inclined portions to which said rubbing strips are secured and means for adjustably securing said plates to said plunger.

15 In witness whereof we have hereunto signed our names.

LOUIS MACKENZIE.

WILLIAM RICHARDSON, JR.
